UNITED STATES PATENT OFFICE

ROSCOE C. HOFFMAN, OF DETROIT, MICHIGAN

DESIGN FOR AN AUTOMOBILE

Application filed April 22, 1932. Serial No. 43,576. Term of patent 7 years.

To all whom it may concern:

Be it known that I, ROSCOE C. HOFFMAN, a citizen of the United States, residing at Detroit, in the county of Wayne and State of Michigan, have invented a new, original, and ornamental Design for an Automobile, of which the following specification is a continuation in part of my application, Serial No. D-42,645, filed January 28, 1932, reference being had to the accompanying drawing forming a part of such specification and in which—

Figure 1 is a side elevational view of an automobile illustrating particularly an ornamental louvre arrangement associated with the body of the automobile in a region immediately in front of the rear fenders thereof.

Figure 2 is an enlarged fragmentary side elevational view of the body region embracing the louvre arrangement as illustrated in the automobile disclosed by Figure 1.

Figure 3 is a fragmentary plan view of the automobile illustrated by Figure 1 and disclosing particularly the appearance of the body in the region of the louvre design therein.

The dominant part of the invention disclosed herein and by the figures of the drawing is the louvre arrangement formed immediately in front of the rear automobile fenders and having a limiting configuration, the curvature of which corresponds approximately to the curvature of the front part of the fenders and portions of the automobile running boards adjacent thereto.

I claim:

The ornamental design for an automobile substantially as shown and described.

ROSCOE C. HOFFMAN.
